PRESS CONTROL MECHANISM

Frank R. Higley, Cleveland Heights, Ohio, assignor to The American Laundry Machinery Company, Norwood, Cincinnati, Ohio, a corporation of Ohio

Application September 23, 1937, Serial No. 165,342

8 Claims. (Cl. 192—131)

This invention relates to improvements in control mechanism for pressing machines, particularly control mechanism of the two-hand safety type.

An object of the present invention is to provide in a pressing machine having power means for closing it and control means for the power means, two safety manuals for actuating the control means and a novel arrangement of fluid means for holding the manuals in unoperated position and in operated position and for moving them from intermediate to full operated position.

Further novel features of my invention will be apparent from the accompanying drawings and specification and the essential features will be set forth in the claims.

In the drawings, Fig. 1 shows an end elevation of a pressing machine in open position with my novel control mechanism shown diagrammatically; Fig. 2 is a similar view showing the press just before reaching safe closed position and the control mechanism in corresponding position; Fig. 3 is a diagrammatic view of the control mechanism of Figs. 1 and 2 in fully operated position corresponding to the closed press; Figs. 4, 5 and 6 show diagrammatically a modified form of control mechanism, the position of the parts in Fig. 4 corresponding to press open position, in Fig. 5 just prior to safe closed position, and in Fig. 6 to fully closed position of the press.

I have illustrated my invention as applied to a pressing machine of the type commonly used in garment and laundry pressing, comprising a frame 10, supporting a bed 11, and a pivoted yoke 12 which carries a head 13 into and out of engagement with the pressing bed when toggle 14 is actuated by fluid motor 15. A spring 16 biases the head toward open position. Pressure fluid is supplied to motor 15 through conduit 17, valve casing 18 and conduit 19. Casing 18 has a normally closed inlet valve closed by the ball 18a and a normally open outlet valve 18b, on a stem 18c which is provided with the yieldable end 18d. No spring is shown for closing the valve 18a as the same will be closed by air pressure if the valve is suitably positioned. For actuation of the valves in casing 18, I provide a pair of spaced safety manuals 20 and 21 connected by toggles 22 and 23 respectively with the ends of a whiffletree 24. This whiffletree has a pin 25 which engages the rod 26 of a diagram motor 27. This motor has a stationary mounting on the frame. This rod extends in a sealed manner through the diaphragm 28 so as to engage the valve stem 18c to which it

is pinned. Stops 28 limit the outward movement of the toggles 22 and 23 and stop 29 limits the inward movement.

Means is provided for preventing movement of toggles 22 and 23 past their center line before the press is safely closed. This means comprises a block 30 which forms part of a bell crank 31 pivotally mounted on the press and connected with rod 32 which in turn passes through slotted bracket 33 on toggle 14. Rod 32 is provided with collars 32a and 32b and is biased by spring 34 to hold the block 30 in the position of Figs. 1 and 2. A conduit 35 connects conduit 19 with the chamber 36 of motor 27. A reducing valve 38 may be placed in conduit 35 to make the operation of the manuals easier.

With the press in the open position of Fig. 1, the operator actuates manuals 20 and 21 from the position of Fig. 1 to that of Fig. 2 where the block 30 stops them short of center line position. Pin 25 on the whiffletree engages rod 26, thus moving the valves in casing 18 to their actuated position and supplying pressure fluid through conduit 17, valve casing 18 and conduit 19 to motor 15. Operation of both manuals coincidentally is required to move the valves in casing 18 to their actuated position because of the whiffletree connection and the gap between pin 25 and rod 26. As soon as the valves in casing 18 are actuated fluid from conduit 19 also passes through conduit 35 to chamber 36 of motor 27. This causes the diaphragm 21a which is rigidly connected to rod 26 to exert a pressure against pin 25 tending to return the manuals to the position of Fig. 1 if either of them is released. The fluid pressure against the valve parts in casing 18 also exerts a force tending to return the manuals. Upon the press reaching safe closed position the block 30 is withdrawn, which can be felt by the operator as she presses on the manuals 20 and 21. Second stage operation of the manuals is then possible, moving them to the over-center position of Fig. 3 where the movement is limited by the fixed stop 29. Upon reaching this position the pressure in chamber 36 of motor 27 now acts to hold the manuals in their over-center position and the operator may release them and the press will remain closed.

The additional motion necessary to move the toggles 22 and 23 from the position of Fig. 2 to that of Fig. 3 with the valve 18b already in closed position, is made possible by the yielding valve stem end 18d.

In the modification of Figs. 4 to 6, the control mechanism is substantially the same ex-

cept for the supply of fluid to the holding diaphragm motor. Therefore all of the parts having similar functions have been given similar reference characters. In this modification, however, conduit 17 communicates by conduit 31, valve 38 and conduit 39 to the chamber 36 in the holding motor 27. This supplies line pressure at all times to chamber 36 as against the first form where fluid pressure is supplied to chamber 36 only after the valves in casing 18 are actuated. Preferably the valve 38 is a reducing valve so as to decrease the pressure in chamber 36 to the point where it is easier for the operator to actuate the manuals but it will be understood the pressure is sufficient to hold the manuals in the position of Fig. 4 or that of Fig. 6. It is thought further description of the operation of this modification is unnecessary.

In either modification, to open the press it is only necessary to return one of the manuals to the position of Fig. 1 or Fig. 4. This permits the valves to return to "off" position under the influence of fluid pressure.

What I claim is:

1. In a pressing machine having coacting relatively movable pressing members and power actuating means therefor, a control member for said power means normally in power cut-off position, a pair of spaced safety manuals, an equalizer bar having intermediate its ends an operative connection with said control member, toggles connecting the manuals with opposite ends of said bar, said toggles being arranged to move over-center by movement of said manuals from unoperated to operated position, and servo-motor means for holding said toggles over-center.

2. In a pressing machine having coacting relatively movable pressing members and power actuating means therefor, a control member for said power means normally in power cut-off position, a pair of spaced safety manuals, an equalizer bar having intermediate its ends an operative connection with said control member, toggles connecting the manuals with opposite ends of said bar, said toggles being arranged to move over-center by movement of said manuals from unoperated to operated position, said manuals having a first stage of movement placing said toggles short of center position and adapted to move said control member to power supply position and having a second stage of movement placing said toggles over center and adapted to hold said control member in power supply position, means preventing second stage movement of said manuals until said pressing members reach safe-closed position, and servo-motor means for holding said toggles in over center position.

3. In a pressing machine having coacting relatively movable pressing members and fluid power means for causing said relative movement, a fluid supply for said power means including a normally closed inlet valve, a pair of spaced safety manuals movable to full operated position and to an intermediate position short of full operated position, an operative connection between said manuals and valve requiring movement of both manuals conjointly to intermediate position to open said valve, servo-motor means for holding said manuals in full operated position only when they are moved beyond their intermediate position, and means preventing movement of said manuals beyond intermediate position until said pressing members reach safe closed position.

4. The combination of claim 3 wherein said servo-motor is constantly supplied with pressure fluid.

5. The combination of claim 3 wherein the supply of fluid for said servo-motor includes said normally closed inlet valve, whereby fluid is supplied to said servo-motor only after said valve is opened.

6. In a pressing machine having coacting relatively movable pressing members and power actuating means therefor, control means for said power means normally in power cut-off position, manual means including a pair of spaced safety manuals having two stages of operation, a first stage during which said manuals are returnable to inoperative position upon their release by an operator and a second stage during which said manuals are maintained in operated position independently of the operator, operative connections between said manual means and said control means requiring conjoint operation of both manuals through said first stage of operation to move said control means to power supply position, servo-motor means for holding said manual means in operated position only after second stage operation of said manual means, and means preventing second stage actuation of said manual means until said pressing members reach safe-closed position.

7. In a pressing machine having coacting relatively movable pressing members and fluid power means for causing said relative movement, fluid supply for said power means including a normally closed inlet valve and a normally open outlet valve operable by a common stem, an equalizer bar having intermediate its ends an operative connection with said valve stem, a pair of spaced safety manuals, each connected to an end of said bar by a toggle, the parts being so arranged that movement of said toggles short of central straightened position moves said stem to open said inlet valve and to close said outlet valve, means preventing movement of said toggles over center until said pressing members reach safe-closed position, and a servo-motor acting against said equalizer bar and toggles to hold said toggles on either side of center position to which they may be moved.

8. In a pressing machine having a pair of relatively movable coacting pressing members and fluid actuated operating means therefor, a control valve for said means normally in fluid cut-off position and having a fluid supply position beyond which it cannot be moved, an equalizer bar operatively associated with said valve, two toggles connected one with each end of said bar, manual means for actuating said toggles, said toggles normally breaking to one side of center when said valve is in cut-off position, said toggles being so arranged that movement of both of them to short-of-straightened position moves said valve to supply position, means limiting said toggles to an overstraightened position for holding said valve in supply position, and means forming a pressure fluid cushion between said bar and said valve adapted to be compressed when said toggles move from short-of-straightened to overstraightened position and to hold said toggles in overstraightened position against said limiting means.

FRANK R. HIGLEY.
